UNITED STATES PATENT OFFICE.

JAMES B. KIRBY, OF CLEVELAND, OHIO.

WASHING-MACHINE.

1,277,603.

Specification of Letters Patent. Patented Sept. 3, 1918.

Application filed January 28, 1915. Serial No. 4,906.

To all whom it may concern:

Be it known that I, JAMES B. KIRBY, a citizen of the United States, residing at Cleveland, in the county of Cuyahoga and State of Ohio, have invented a certain new and useful Improvement in Washing-Machines, of which the following is a full, clear, and exact description, reference being had to the accompanying drawings.

10 This invention relates to washing machines and has for its objects the provision of new and improved mechanism whereby clothing and fabrics can be efficiently and rapidly washed and all free water removed 15 therefrom with a minimum of care, exertion, wear, tear, and handling. To this end the invention comprises novel constructions and expedients for forcing the cleansing fluid through the fabric, while constantly 20 changing the position of the fabric so as to expose all portions thereof to the cleansing fluid, also for removing all adherent water therefrom by centrifugal motion and without removing the clothing from the washing 25 receptacle. Further objects of the invention relate to the provision of a simple, strong and reliable mechanical construction whereby the power necessary to the above operation may be applied, and whereby the 30 speed of movement of the members may be varied as necessary for the purposes in view, and whereby the machine may be rendered safe in the hands of careless, unskilled, or inattentive workers. Additional objects are 35 the provision of mechanism adapted to be operated with a minimum of power, and to employ a minimum quantity of cleansing liquid while further objects and advantages will become apparent as the description proceeds.

Generally speaking my invention may be defined as consisting of the combinations and constructions recited in the claims here-to annexed and illustrated, in one embodiment, in the drawings accompanying and forming a part of this application, wherein: Figure 1 is a right-hand end elevation of a machine constructed in accordance with my invention, a portion of the top being broken away to show the washing drum, the parts being illustrated in washing position; Fig. 2 is a vertical, sectional view through the center of said machine, the plane of section being parallel to the end shown in Fig. 1; Fig. 3 is a view similar to Fig. 1 but showing the parts in wringing or drying posi-

tion; Fig. 4 is a front elevational view of my improved washing machine, the parts being shown in the position illustrated in Figs. 1 and 2; Fig. 5 is a detail view of the controlling mechanism drawn to enlarged scale and showing the same in washing position; Fig. 6 is a similar view showing the positions assumed by the parts when the drum is elevated but prior to the elevation of the motor to increase its speed; Fig. 7 is a view of the same parts showing their relative positions when the motor is elevated to increase the speed; Fig. 8 is a detail perspective view of the operating mechanism; Fig. 9 is a detail view illustrating the operation of the folding connecting rod; Fig. 10 is a top plan view of the complete machine; Fig. 11 is a horizontal, cross-sectional view taken upon the line 11-11 of Fig. 2 and looking downwardly; Fig. 12 is a perspective view of the stopping mechanism drawn to enlarged scale.

Describing the parts by reference characters, 1 represents the outer casing or receptacle of my improved machine, the same being preferably of metal and having a cylindrical side wall and a flat bottom wall 2, the whole being supported at a convenient height by a suitable framework. This framework may conveniently take the form of a spider 3 (see Fig. 2) having four equidistant brackets 4-4 (Fig. 10) adapted for the reception of angle iron legs 5-5 connected by suitable braces 6. The center of this spider is apertured for the passage of the bearing sleeve 7, which also passes through an aperture in the bottom of the tub and is secured thereto in any convenient leak-proof manner. Between the arms 3-3 of the spider the casing is exposed to the action of suitable burners 8, so that the clothing may be boiled without removal or handling.

Inside the casing the bearing sleeve 7 is preferably prolonged upwardly in the form of a hollow extension 9 of a height sufficient to project above the greatest amount of liquid intended to be used, and within this extension is rotatably and slidably journaled the vertical main shaft 10, the upper end of said shaft being flattened or squared at 11 for the reception of the washing container or drum. This drum consists of a rigid cylindrical member preferably made of foraminous material such as heavy screen cloth and has a circular flat bottom wall 12.

and upstanding side walls 13. The diameter of this drum is slightly less than that of the casing so as to permit it to be moved freely therein, but its height is materially less than that of the casing for a purpose to be hereafter explained. This drum or container comprises a hollow central vertical sleeve 14 adapted to receive the extension 9 and having secured to its lower end a plurality of rigid radial arms 15 whose outer ends are attached to an annulus 16 which receives the screening of which the side wall is made. The upper end of the sleeve 14 is reduced and fitted to the end of the shaft 10 as shown at 17 and secured thereto in any suitable manner as by means of the nut 18. The upper edge of the wall 13 is preferably received within a smooth metallic rim 19 whereby the drum is stiffened and injury to the user's hand is avoided.

The exterior of the bearing 7 is made of cylindrical shape as shown at 25 (Fig. 2) for the reception of the rotatable hub 26 of the friction wheel 27 whose spokes 28 are downwardly curved or dished as shown in Figs. 1 to 4, inclusive, for the reception of the gearing. Below this hub the bearing 7 is reduced in size as shown at 30 for the reception of a collar 31, here shown as fitting partly within the lower end of the hub 26 and as secured against longitudinal movement by the nut 32. Projecting radially from one side of this collar is a fixed stud 33 on which is rotatably journaled a bevel gear 34 meshing with a second bevel gear 35 rigidly secured to the hub 26, and projecting from the face of the gear 34 is a crank pin 36 to which is articulated the connecting rod 37. On the other side of the collar 31 is formed an extension 38 forming a counterweight adapted to counter-balance the weight of the gear 34 and its connected parts and to this is attached the stop rod 39 which will be referred to hereafter.

Rigidly secured to the lower end of the shaft 10 as by the set screw 40 is a bracket 41 which carries a transverse wrist pin 42 parallel to the pin 36, and upon this pin is pivoted the lower connecting rod member 43. The two members 37 and 43 of this connecting rod are articulated together at 44 upon an axis parallel to the pins 36 and 42 so as to form a kind of toggle joint, one of the members carrying a finger 45 adapted when the toggle is straightened to engage the other member and prevent any material movement beyond the dead center. At the opposite side of the pivot 44 from this finger the connecting rod members are preferably provided with a pair of bosses 46-46 connected by a tension spring 47 which tends to hold the toggle in either assumed condition. As a result of this construction it will be seen that upon the rotation of the gear wheel 34, the collar 31 being suitably

restrained against movement, the pin 42 will be alternately raised and lowered, carrying with it the shaft 10 and the drum or container, while upon the release of the collar 31 the tendency will be for the shaft to 70 rotate together with the gear wheel 34, since the pins 36 and 42 are necessarily parallel at all times.

Rigidly secured to the two forward legs of the stand are two parallel rods 50 and 51, one above the other. Pivoted upon the former is a depending arm 52 having at its rearward side a pair of vertically spaced eyes 53-53 said arm terminating at its lower end in a flat push plate 54. Received in the eyes 53-53 is a vertical rod 55 on which is mounted a horizontal arm 56 whose rearward end carries the motor shelf 57. This shelf carries the motor 58 whose shaft bears the friction disk 59 which engages the friction ring 60 carried by the rim of the wheel 27. Upon the opposite side of the stud 55 the arm 56 is extended in the form of a bracket 61 adjacent to which is an extension 62 upon the side of the arm 52. Secured to this extension is a bolt 63 which passes between a pair of fingers 64 carried by this bracket and between the bolt head and the fingers is a spring 65 which tends normally to draw the arm 56 toward the frame and so press the disk 59 against the ring 60. Journaled along this arm is a rock shaft 66, having at one end the upturned handle 66^a and at the other the cam 67. By rocking this shaft so as to force the cam 100 against the extension 62 the bracket 61 is wedged away from the arm against the tension of the spring 65 and the motor is disconnected from the friction wheel thus stopping the machine.

Journaled upon the rod 51 is a sleeve 70 having at its outer side the pedal 71 and having at its inner side the arm 72, the latter being so shaped as to come beneath the shaft 10. The inner extremity of this arm is provided with a flat engaging portion 73 adapted to be brought into contact with a loose button 74 carried by the lower end of the shaft whose function will be described later. Also this arm carries an upwardly projecting stop 75 adapted to engage the rod 39 to hold the collar 31 against rotation. The arm 72 further carries a bracket 76 to which is pivoted the releasing pedal 77. This last named pedal is integral with a depending arcuate portion 78. The releasing pedal 77 is normally held in raised position by means of the spring 79. Carried by the arm 52 and projecting rearwardly from the portion 54 thereof is a bracket portion 83 125 whose curvature is substantially defined by the axis 50. Normally the curved portion 78 of the releasing pedal extends over the rearward edge of this curved bracket as illustrated in Figs. 1 and 5, so as to prevent any 130

movement of the arm 52 about its pivot the length of the portion 78 being such that when the top is elevated by the depression of the pedal 71, this portion 78 will snap 5 over the rearward edge of the bracket 83 when the tub reaches its highest point as illustrated in Figs. 3 and 6. It will thus be seen that until the elevating pedal 71 has been moved to the position shown in Figs. 10 3 and 6 it will be impossible to swing the arm 52 around its pivot 50, but that after the raising of the drum or container has been effected it will be automatically locked 15 against returning and the arm 52 will be free to be moved at will.

For the purpose of swinging the arm 52 a sleeve 84 is journaled upon the rod 51, said sleeve having at its lower side a pedal 85 and having at its lower side a depending 20 finger 86 pressing against the plate portion 54 of the arm 52. The button 74 heretofore mentioned is secured at the lower end of the shaft with a possibility of a certain amount of vertical movement, and the lower member 25 43 of the connecting rod is formed at one side with a toe 90 projecting thereover. The elevation of the arm 72 consequent upon the depression of the pedal 71 serves first to raise the button 74 which presses against 30 the toe 90 and breaks the toggle joint, to the position shown in Figs. 3, 6, and 9, the shaft 10 sliding freely through the bearing 7 and elevating the drum or container to the position shown in Fig. 3. The movement of the 35 pedal 71 also swings the stop rod 75 away from the arm 39 thus permitting the collar 31 to rotate freely, whereupon the entire system commences to revolve with the wheel 27. This elevation of the container brings 40 the same above the surface of the liquid in the casing so that the clothes may drain, the catch 78 serving both to prevent their accidental return into the liquid and also to free the speed changing devices so that the drum 45 speed may be increased upon depressing the speed pedal 85 and the clothing wrung centrifugally. Furthermore, this catch prevents the lowering of the container until the friction disk has been returned to low speed 50 position, which is important since the dropping of the rapidly revolving drum into the liquid in the casing would certainly throw most of that liquid out on the floor and might entail much graver consequences. 55 The lowering of the motor, no matter how quickly done, will exercise a braking action on the drum or container so that the most serious effect of an immediate operation of the releasing pedal is to drop the dry clothes 60 back into the water, which the user will soon learn not to do. The only exception to this braking action occurs when the friction disk is thrown away from the wheel while in high speed position, in which case the momentum 65 of the drum causes it to rotate for a con-

siderable time. However the dropping of the same into the liquid is attended with no danger since the energy available is merely that of the rotating tub and is not reinforced by motor power.

However it is desirable that the reciprocating motion should not be recommenced until the rate of movement has fallen comparatively low, since otherwise the abrupt stoppage of one movement and the sudden beginning of another will surely break something. Therefore I preferably pivot the arm 39 to the collar 31 as shown at 93, also forming the center of gravity of the arm at the point outside of and below this 75 pivot so that upon beginning to rotate it will act as a governor and rise as shown in Figs. 6 and 7, so that even if the stop rod 75 be returned prematurely to obstructing 80 position, it will not intercept the movement 85 of this arm until the rotation has reached a safe value. Also the centrifugal action elevates the end of this arm into the wheel 27, and avoids all danger of its catching the 90 clothing or body of the operator.

It will be noted that the washing movement consists of a vertical reciprocation imparted to the drum or container, the bottom of the same being of perforated or foraminous material. This movement alone 95 has some washing value, but after long experiment the washing mechanism that commends itself particularly to me is that illustrated in Figs. 2 and 10 hereof. According to this part of my invention the exterior of 100 the sleeve 14 is made cylindrical and a collar 95 is loosely slipped thereon, said collar being formed with lateral arms 96 provided with heavy bells, cones, or beaters 97. Beneath the collar 95 is introduced a compression spring 98 whose lower end is preferably secured rigidly to the sleeve as by a boss 99. The weight of the bells or beaters, the stiffness of the spring 98, and the frequency 105 of reciprocation being rightly selected, the 110 bells or beating members will acquire a motion wholly independent of the container though of the same frequency and lagging slightly in phase. Thus when the container rises the inertia of the beaters causes the 115 spring 98 to be compressed and upon the arrival of the container at the highest point of its path, the beaters continue on upwardly for a moment while the container descends. The descending movement of the container 120 therefore precedes the downward movement of the bells, and the upward rush of the liquid through the container bottom loosens the fabrics and rearranges the same prior to the arrival of the bells, and also leaves 125 the fabrics floating loosely where they will be most affected by the bells.

In addition the helical nature of the spring causes the same to twist slightly in contracting and expanding, which action 130

causes the collar 95 to be shifted angularly slightly with each reciprocation with the result that the bells or beaters progress steadily around the container and never 5 strike the same place twice in succession.

While I have shown beaters of bell or cone form, any kind may be used within the limits of my invention, though I prefer these by reason of their undoubted efficiency.

10 Also while I have shown only two of the same, any convenient number can be employed, provided only that they are properly balanced and distributed. The downward movement of the tub into the water 15 loosens and removes the clothing and fabrics from the bottom of the same and prevents their being beaten into adherence therewith as in some prior machines, this action being particularly marked by reason 20 of the fact that the movement of the container is independent of that of the beaters, and the downward movement of the former precedes the downward movement of the latter. Also the lateral shifting heretofore 25 mentioned coöperates with this motion to distribute the clothing thus rendering unimportant the care with which the same is introduced into the container and causing them all to become subjected to the washing 30 action. This distributing action is peculiarly fortunate in connection with the centrifugal wringing, since it prevents any such lack of balance as might cause vibration or accident.

35 The weight and area of the beating element, the stiffness of the spring, and the frequency of the reciprocation are all so closely related that the change of one requires the change of all, and are so dependent upon empirical conditions such as amplitude of movement as to render mathematical computation impossible. The best plan is to make the beating element of rather heavy weight, choose a spring that will vibrate well therewith, and change the speed 40 of the reciprocation until the proper results are obtained, this being easily effected by sliding the arm 56 up or down the rod 55. Such trial, may then indicate the desirability 45 of changing the weight of the system or the stiffness of the spring.

For purposes of completeness I may note that I now employ a movable element weighing fifteen pounds (6.8 kilograms) and comprising 55 two bells each nine inches (22.8 centimeters) in diameter; a spring six inches (15.2 centimeters) long when unloaded and requiring a load of thirty pounds to compress it one inch (5.36 kilograms) per centimeter; a reciprocation of about 125 complete 60 cycles per minute, and an amplitude or stroke of three inches (7.6 centimeters). Under these conditions the movable element is given a throw of about seven inches (17.8 centimeters) when the container is empty or

not too heavily charged with clothing. The shape of the bells has something to do with the operation since a low, flat, or coniform beater impedes the operation by offering too great a resistance to entrance into the liquid, 70 while a deeper and rounder form such as I have illustrated traps the air and permits the compression of the same, this not only preventing splashing and affording a more uniform washing operation, but by its expansion assisting in the succeeding upward movement of the beating element.

It is not necessary to remove the beating devices before wringing although the same can be done if desired, nor even to remove 80 the cover from the casing. Also it is not imperative that the drum or container have a perforated bottom wall, though without it a considerable part of the advantage of my washing devices would be lost. Also it is 85 not imperative that the sidewall of the drum or container be of foraminous material since corrugated walls if slightly inclined would throw off the water sufficiently for wringing purposes. Furthermore it would not be 90 necessary to elevate the inner tub or container to free it from the washing liquid in case the user was satisfied to draw off and discard or store that liquid, though the arrangement I have shown permits the washing to be done in instalments, the same wash water being employed. However between successive washings it is sometimes desirable to perform a rinsing, bluing or like operation and to wring the clothes so treated. 100 Also in such case it is frequently desirable to keep such foreign liquid from cooling or contaminating the wash water. For this purpose I may provide the casing with an annular gutter 100 located just below the bottom of the container when the same is in wringing position. I provide this gutter with a discharge cock 101 independent of the main discharge cock 102, and when this is opened the wringing mechanism can be 105 employed with a minimum of contamination of the wash water.

The elevation of the drum out of the liquid is done without the necessity of stopping the machine. The friction drive renders the 115 increase of speed very even and convenient, avoids all shifting of gears, limits the acceleration to the friction present thereby preventing overstrain of the parts, and prevents the throwing of an undue load upon 120 the motor whereby fuses or wiring would be burned out. Also in case the motor is released to its low speed position with undue suddenness the drive permits the necessary slipping consequent on a more gradual 125 slowing of the drum.

The employment of a central sleeve 9 avoids all difficulty from leaky packings and prevents any lubricating oil from finding its way into the water. Functionally, however, 130

many other constructions could be employed. Also I contemplate the use of a suitable pan or shell carried by the lower end of the shaft 10 for shielding the mechanism and preventing the dropping of oil.

While, owing to the desire for brevity, I have described my invention with reference only to this single embodiment, it will be obvious that a great many changes in point 10 of detail could be made within the scope of my invention, and that embodiments differing materially in many ways from that here shown fall within the scope of my inventive idea. Accordingly I intend my description 15 as purely illustrative and not restrictive, as I do not limit myself to any detail of construction, operation or arrangement except as the same may be specifically recited in the claims hereto annexed or may be rendered 20 necessary by the prior state of the art.

Having thus described my invention, what I claim is:—

1. In a washing machine, a casing, a perforated container therein, means for reciprocating said container in the lower part 25 of said casing for washing fabrics therein, and means for rotating said container at high speed whereby said fabrics may be wrung without removal from the container. 30 2. In a washing machine, a casing adapted to hold cleansing liquid, a container within said casing and having its walls formed for the discharge of liquid, means co-operative with said container for washing fabrics 35 therein, means for elevating said container above the level of the liquid in said casing, automatic devices for preventing the return of said container to liquid contacting position, mechanism for rotating said container 40 at high speed whereby adherent liquid may be removed from the fabrics therein, and an operative connection between said devices and said mechanism for preventing the operation of said mechanism except during 45 the action of said devices.

3. In a washing machine, a casing adapted to hold cleansing liquid, a container therein adapted to receive the clothing or fabrics to be washed, said container having 50 perforated walls, a shaft rigidly secured to said container, means for moving said shaft to bring said container into contact with the liquid in said casing for washing said fabrics, means for moving said shaft so as 55 to elevate said container above the liquid, means for thereafter rotating said container at high speed, and means governed by the position of said shaft for preventing the application of rotative power thereto in high. 60 60 speed driving relation while said container is in liquid contacting position.

4. In a washing machine, a casing adapted to hold cleansing liquid, a container therein and adapted to receive the clothing or fabrics to be washed, said container hav-

ing a perforated bottom, means for reciprocating said container in the liquid, means for changing the relative position of the container and liquid level so as to bring said container out of the liquid, and means 70 for rotating said container at high speed.

5. In a washing machine, a casing adapted to hold cleansing liquid, a container therein adapted to receive the clothing or fabrics to be washed, said container having 75 perforated walls, means for submerging said container in the liquid, means for moving it therein, means for raising said container out of the liquid, and means independent of said raising means for thereafter 80 rotating said container at high speed.

6. A washing machine comprising a casing, a circular tub in said casing and movable to and between upper and lower positions therein, means for washing clothing 85 contained in said tub while the same is in the lower position, means for elevating said tub to its upper position, means for rotating said tub at high speed while so elevated, and an annular gutter carried by said casing above the washing position and adapted to catch the water thrown from said tub.

7. In a washing machine, a casing adapted to hold cleansing liquid in its lower part, a container in said casing and adapted to 95 receive the clothing or fabrics to be washed, said container having a foraminous wall, means whereby said container may be brought either below or above the level of the liquid and without removing the liquid 100 from the casing, means for moving said container while in contact with the liquid whereby the clothing or fabrics therein may be washed, means for revolving said container rapidly while out of contact with the 105 liquid whereby the fabrics may be dried, and devices for preventing any increase of speed of said revolving mechanism during the time that said container is in liquid contacting position.

8. In a washing machine, a casing adapted to hold cleansing liquid in its lower part, a container rotatable in said casing and adapted to receive the clothing or fabrics to be washed, said container having a 115 foraminous wall, means whereby said container may be brought either below or above the level of the liquid and without removing the liquid from the casing, a continuously rotating driving element, gearing connecting said element to said container so as to move the same at comparatively low speed while in contact with the liquid, and for revolving said container at comparatively high speed when out of contact with 120 the liquid, and means for preventing the connection of said driving element to said container in high speed relation during the time that said container is in liquid contacting position.

- 6 9. In a washing machine, a casing adapted to hold cleansing liquid in its lower part, a container therein adapted to receive the clothing or fabrics to be washed and to be supported in either the lower or the upper part of said casing, said container having a perforated wall, means coöperating with said container for washing the clothing or fabrics therein, while in the lower part of 5 said casing, means for elevating said container above the liquid level, means for thereafter rotating said container at high speed, and means carried by the upper part of said casing for catching and discharging the liquid thrown from said container before it reaches the bottom part of the casing.
- 10 10. In a washing machine, a casing adapted to hold cleansing liquid in its lower part, a container rotatable in said casing and adapted to receive the clothing or fabrics to be washed, means whereby said container may be brought either in contact with the liquid or above the liquid level and without removing the liquid from the casing, mechanism including a friction wheel and disk for moving said container at low speed while in contact with the liquid, means operative while said container is out of liquid contacting position for changing the relative position of said disk and wheel whereby said container may be rotated rapidly, and means for preventing such shifting until after said container has been brought above the liquid level.
- 15 11. A washing machine comprising a casing for holding liquid, a vertical shaft in said casing, a container carried by said shaft for holding clothing, a wheel of large diameter coaxial with said shaft, a driving wheel contacting with said first wheel, and mechanism connecting said first wheel and shaft adapted to operate said shaft at a speed slower than said first wheel for washing purposes and at a speed equal to said first wheel for drying purposes.
- 20 12. A washing machine comprising a casing for holding liquid and having an elongated vertical sleeve projecting through its bottom, a shaft journaled in said sleeve, a circular container secured to the upper end of said shaft and having an apertured wall, means whereby said container may be brought either above or below the level of the liquid and without removing the liquid 25 from the casing, and mechanism outside of and beneath said casing whereby said shaft may be reciprocated at low speed for washing purposes or revolved at high speed for drying purposes.
- 30 13. In a washing machine, a substantially cylindrical liquid-containing casing having an axial bearing in one of its flat sides, a shaft reciprocably and rotatably journaled in said bearing, a circular container within 35 said casing and secured axially to said shaft, a drive wheel journaled to said bearing, mechanism operative during the time that said shaft is in lowered position for imparting a reciprocating motion thereto upon rotation of said drive wheel, and mechanism operative during the time that said shaft is in raised position for imparting rotary movement to said shaft upon rotation of said drive wheel.
- 40 14. In a washing machine, a casing, a cylindrical container located therein with its axis substantially vertical and movable between upper and lower positions in said container, a driving wheel outside of said casing, mechanism operated by said driving wheel whereby articles in said container may be washed while in the lower part of said casing, mechanism also including said wheel whereby said container may be rotated at high speed while in the upper part of said 45 casing, and means automatically operative upon the raising of said container for stopping the operation of said first mechanism and starting the operation of said second mechanism.
- 45 15. In a washing machine, a casing adapted to hold cleansing liquid, a container therein adapted to receive the clothing or fabrics to be washed, said casing being of greater height than said container and said container having a perforated wall, means for moving said container into contact with the liquid in said casing for washing the fabrics therein, means for elevating said container above the liquid, means for thereafter rotating said container at high speed, and interconnecting devices between said elevating means and said rotation controlling means for preventing lowering of said container until after the application of high speed 50 power thereto has ceased.
- 50 16. In a washing machine, a casing adapted to hold cleansing liquid in its lower part, a container in said casing and adapted to receive the clothing or fabrics to be washed, said container having a perforated wall and said casing being of greater vertical height than said container, means for raising and lowering said container within said casing, means operative while said container is in the lower part of said casing for imparting a reciprocating movement thereto, means operative while said container is in the upper part of said casing for imparting a rotary movement thereto, and means operative automatically upon the elevation of said casing for changing from reciprocating to rotary movement.
- 55 17. In a washing machine, a casing, a circular container inside said casing, means for raising and lowering said container, a power source operating always in one direction and at a uniform speed, and mechanism connecting said source and container and adapted when said container is in lowered position to 60

impart a reciprocating movement thereto and when in elevated position to impart a rotary motion thereto.

18. In a washing machine, a casing, a circular container therein, means for raising and lowering said container, a rotating member, mechanism connecting said member and container and adapted when said container is in the lower part of said casing to impart a reciprocating motion thereto, said reciprocating mechanism being arranged to be released upon the elevation of said container, and means operative upon the release of said reciprocating mechanism for effecting a driving connection between said rotating member and container whereby the latter will be revolved continuously.

19. In a washing machine, a casing, a circular container inside said casing, means for raising and lowering said container, a power source operating always in one direction and at a uniform speed, mechanism connecting said source and container and adapted when said container is in lowered position to impart a reciprocating movement thereto and when in elevated position to impart a rotary motion thereto, and means operative to delay the change from rotary to reciprocating movement after the lowering of the container until the rotative speed shall have fallen to a predetermined amount.

20. In a washing machine, a casing, a circular container therein, means for raising and lowering said container, a rotary member, a driving wheel operated thereby, mechanism connecting said driving wheel and container adapted when said container is in lowered position to impart a slow washing movement thereto and when in raised position to impart a rotary movement thereto, means for effecting a change in the speed ratio between said rotary member and driving wheel, and mechanism for preventing the operation of said last means excepting when said container is in raised position.

21. In a washing machine, a casing for holding liquid, a shaft projecting into said casing, a circular container in said casing and operatively connected to said shaft, mechanism operatively connected to said shaft for agitating clothing within said container for washing purposes, mechanism including said shaft whereby said container may be given a rapid rotating movement for drying purposes, and devices for preventing increasing the speed of said shaft unless said container is first raised to an elevated position in said casing.

22. In a washing machine, a casing for holding liquid, a shaft projecting into said casing, a cylindrical foraminous container in said casing and operatively connected to said shaft, a friction wheel outside of said casing, means whereby said container may be brought either below or above the level

of the liquid and without removing the liquid from the casing, means operative during the time that said container is in liquid contacting position for gearing said wheel to said shaft in slow moving relation, means operative during the time that said container is out of liquid contacting position for clutching said wheel to said shaft whereby said container may be given a rapid movement for wringing purposes, a friction disk in driving contact with said wheel and normally maintained in low speed relation thereto, means for moving said disk relatively to said wheel whereby the speed of said wheel may be increased, and devices for preventing the operation of said last named means except when said wheel is secured directly to said shaft.

23. In a washing machine, a casing adapted to hold cleansing liquid in its lower part, said casing having a vertical bearing in its bottom wall, a support for said casing, a shaft slidably and rotatably mounted in said bearing, a cylindrical container secured to the upper end of said shaft, within said casing, pedal means carried by said support for raising and lowering said shaft so as to support said container either in or out of the liquid in said casing, mechanism operatively connected to said shaft whereby the container may be given a vibratory movement while in lowered position and a rotary movement while in raised position, and means operative upon the movement of said pedal for changing from one movement to the other.

24. In a washing machine, a cylindrical casing adapted to hold cleansing liquid, said casing having an axial bearing in its bottom wall, a support for said casing, a shaft journaled in said bearing, a cylindrical container secured to the upper end of said shaft, said container having liquid discharging walls and an open top, a pedal pivoted to said support for raising and lowering said container into and out of the liquid in said casing, means operatively connected to said shaft whereby the container may be given a different kind of movement while in said liquid than while elevated, means operated by the movement of said pedal for shifting from one kind of movement to the other, and an automatic catch for retaining said pedal in container-elevating position.

25. In a washing machine, a casing adapted to hold cleansing liquid in its lower part, said casing having a bearing in its bottom wall, a shaft slidably and rotatably mounted in said bearing, a circular container secured to said shaft within the casing, a driving wheel surrounding said shaft outside of said casing, a driving element operatively engaged with said wheel, means for varying the relative speed ratio between said driving element and said wheel, means for raising

and lowering said shaft relatively to said wheel, and means for connecting said wheel in different operative relations to said shaft in raised and in lowered position.

5 26. In a washing machine, a casing adapted to hold cleansing liquid in its lower part, said casing having a bearing in its bottom wall, a shaft slidably and rotatably mounted in said bearing, a foraminous container secured to said shaft within the casing, a wheel rotatably supported coaxially with said shaft, a driving element operatively engaged with said wheel, and connections between said wheel and shaft whereby a movement of continuous rotation of said wheel imparts to said container a vibratory movement.

20 27. In a washing machine, a casing adapted to hold washing liquid, a support for said casing, a bearing member secured in the bottom wall of said casing and depending therefrom, a vertical shaft slidably and rotatably journaled inside of said bearing, a friction wheel rotatably journaled upon the exterior 25 of said bearing, a friction disk carried by said support adjacent to the edge of said wheel, means for raising and lowering said shaft, means for transmitting the motion of said wheel to said shaft in either of its positions, means for shifting the relative position of said disk and wheel, means for preventing such shifting excepting during the raised condition of said shaft, and a circular container secured to the upper end of said shaft.

30 28. In a washing machine, a cylindrical casing adapted to hold washing liquid in its lower part, a bearing member axially secured in the bottom wall of said casing and projecting therefrom, a shaft journaled inside of said bearing, a circular container secured to the end of said shaft within said casing, a friction wheel rotatably journaled upon the exterior of said bearing, a friction 35 disk operatively supported adjacent to the edge of said wheel, means for raising and lowering said container relatively to the liquid in said casing, means for automatically locking said container in raised position, operative connections between said wheel and shaft, means for shifting the relative position of said disk and wheel, and means for preventing such shifting excepting after the operation of said locking means.

40 29. In a washing machine, a casing adapted to hold cleansing liquid in its lower part, said casing having a vertical bearing in its bottom wall, a support for said casing, a shaft slidably and rotatably mounted in said bearing, a friction wheel operatively connected to said shaft, a friction disk operatively engaged with said wheel, means for driving said disk, a lever pivoted to said support and adapted to raise and lower said

50 shaft, a second lever pivoted to said support and adapted to shift said disk relatively to said wheel, a circular container secured to the end of said shaft within said casing, and means for preventing the operation of 70 said second lever excepting after said first lever has been operated.

55 30. In a washing machine, a casing adapted to hold cleansing liquid, said casing having a bearing in its bottom wall, a support 75 for said casing, a shaft in said bearing, a friction wheel operatively connected to said shaft a friction disk operatively engaged with said wheel, means for driving said disk, a circular container secured to the end 80 of said shaft within said casing, said container being supported so as to be raised and lowered relatively to the liquid, a lever pivoted to said support and adapted to shift the relative position of said disk and wheel, 85 and means preventing such shifting excepting after said container has been raised relatively to the liquid and for preventing the lowering of said container until after the return of said wheel and disk to normal 90 position.

95 31. In a washing machine a casing adapted to hold cleansing liquid in its lower part, said casing having a vertical bearing in its bottom wall, a shaft slidably and rotatably 100 mounted in said bearing, a frame supporting said casing, a circular container secured to the upper end of said shaft, power driven means operatively connected to said shaft whereby the same may either be rotated or reciprocated a lever pivoted to said frame and adapted when depressed to raise said shaft, and also to connect said means and shaft in rotating relation, a locking device co-operating with said lever and adapted to 105 retain said shaft and container in elevated position, and a second lever pivoted to said frame and adapted when operated to increase the speed of said device, said last lever being arranged to be operated only 110 after the operation of said first lever.

115 32. In a washing machine, a casing adapted to hold cleansing liquid, said casing having a vertical bearing in its bottom wall, a framework supporting said casing, a shaft 120 slidably and rotatably mounted in said bearing, a friction wheel surrounding said shaft and rotatable in a horizontal plane, an arm pivoted to said frame upon a horizontal axis and having a horizontal shelf projecting 125 therefrom, a motor carried by said shelf and having its shaft horizontal, a friction disk carried by the motor shaft and engaging the edge of said friction wheel, and a lever pivoted to said frame and having a finger engaging said arm whereby the same may be swung about its pivot and said shelf raised.

130 33. In a washing machine, a casing adapted to hold cleansing liquid, said casing having a vertical bearing in its bottom wall, a

- framework supporting said casing, a shaft 5
slidably and rotatably mounted in said bearing, a friction wheel surrounding said shaft and rotatable in a horizontal plane, an arm
5 pivoted to said frame upon a horizontal axis and having a horizontal shelf projecting therefrom, a motor carried by said shelf and having its shaft horizontal, a friction disk carried by the motor shaft and engaging the
10 edge of said friction wheel, the parts being normally arranged so that said wheel engages said disk adjacent to and slightly below the center thereof, a lever pivoted to said framework and arranged when depressed to
15 elevate said shaft, a second lever pivoted to said framework and having a finger engaging said arm and arranged when said second lever is depressed to swing said arm and elevate said motor shelf, and connections between said levers whereby movement of the second lever is prevented prior to the elevation of said shaft. 20
34. In a washing machine, a casing adapted to hold cleansing liquid, a bearing member secured in the bottom wall of said casing and depending therefrom, a vertical shaft journaled inside of said bearing, a driving wheel rotatably journaled upon the exterior of said bearing and rotatable in a horizontal plane, a bevel gear secured to said driving wheel, a second bevel gear pivoted to said bearing member upon a horizontal axis and meshing with said first gear, a connecting rod having one of its ends eccentrically pivoted to said second gear and its other end pivoted to said shaft, and a washing device secured to the upper end of said shaft. 35
35. In a washing machine, a casing adapted to hold cleansing liquid, a bearing member secured in the bottom wall of said casing and depending therefrom, a support for said casing, a vertical shaft journaled inside of said bearing, a driving wheel rotatably journaled upon the exterior of said bearing and rotatable in a horizontal plane, a bevel gear secured to said driving wheel, a collar sleeved upon said bearing and having a horizontal stud, a second bevel gear journaled on said stud and meshing with said first gear, a connecting rod having one end eccentrically pivoted to said second gear and its other end pivoted to said shaft, a perforated container secured to said shaft, and a lever pivoted to said support and adapted when operated to raise said shaft, said lever also having an extension adapted when in depressed position to prevent rotation of said collar. 40
36. In a washing machine, a casing adapted to hold cleansing liquid, a bearing member secured in the bottom wall of said casing and depending therefrom, a vertical shaft journaled inside of said bearing, a driving wheel rotatably journaled upon the exterior of said bearing and rotatable in a horizontal plane, a bevel gear secured to said driving wheel, a collar journaled on said bearing and having a horizontal stud, a second bevel gear journaled on said stud and meshing with said first gear, a connecting rod having one end eccentrically pivoted to said second gear and its other end pivoted to said shaft, a centrifugal member pivoted to said collar, a stop member adapted to engage said centrifugal member when still to prevent movement of said collar, a foraminous container secured to the upper end of said shaft, means for raising and lowering said container, and means for freeing said centrifugal member simultaneously with the raising of said container. 75
37. In a washing machine, a casing adapted to hold cleansing liquid and having a bearing in its lower wall, a vertical shaft slidably mounted in said bearing, a container secured to the upper end of said shaft and having a foraminous lower wall, beating members in said container, and means for imparting to both said beating members and container a regularly timed vertical reciprocating motion. 80
38. In a combined washing machine and centrifuge, a casing adapted to hold cleansing liquid, a container inside said casing and having a foraminous lower wall, beating members in said container, means for imparting to said beating members a vertical reciprocating motion combined with an intermittent motion of progression around said container, and means whereby said container may be rotated rapidly about its axis. 90
39. In a washing machine, a casing adapted to hold cleansing liquid and having a bearing in its lower wall, a vertical shaft slidably mounted in said bearing, a container secured to the upper end of said shaft and having a foraminous lower wall, beating members in said container, means for imparting to both said beating members and said container a regularly timed vertical reciprocating motion, and means for shifting said members angularly at each reciprocation so as to strike at a different place. 100
40. In a combined washing machine and centrifuge, a casing adapted to hold cleansing liquid, a container inside said casing and having a foraminous lower wall, beating members in said container, means for imparting to said beating members a vertical reciprocating motion relatively to said container, means for shifting said members angularly about the container when near the lower limit of each reciprocation, and means whereby said container may be rotated rapidly about its vertical axis. 110
41. In a washing machine, a casing adapted to hold cleansing liquid, a container in said casing and adapted to receive the clothes or fabrics to be washed, said container having a perforated lower wall, means 115

- for reciprocating said container vertically at a fixed rate, beating members in said container and spring means supporting said beating members from said container, the weight of said beating members and the stiffness of said springs being so balanced that said beating members shall have a vibratory motion independent of said container.
42. In a washing machine, a casing adapted to hold cleansing liquid, a container in said casing and adapted to receive the clothes or fabrics to be washed, said container having a foraminous lower wall, a beating member located in said container, a spring carried by said container normally supporting the weight of said beating member and means for reciprocating said container.
43. In a washing machine, a casing adapted to hold cleansing liquid, a container in said casing and adapted to receive the clothes or fabrics to be washed, said container having a perforated lower wall, and a central cylindrical stud, a collar sleeved on said stud and having radial arms, beating members carried by said arms a compression spring surrounding said stud between said collar and the bottom of said container, and means for reciprocating said container vertically at a fixed rate, the weight of said collar and beating members being so related to the stiffness of said spring that a vibratory movement will be imparted thereto by the motion of said container.
44. In a washing machine, a casing adapted to hold cleansing liquid, a container in said casing and adapted to receive the clothes or fabrics to be washed, said container having a perforated lower wall, and a central cylindrical stud, a collar sleeved on said stud and having radial arms, beating members carried by said arms, a spiral compression spring surrounding said stud between said collar and the bottom of said container, the lower end of said spring being non-rotatably secured in place, and means for reciprocating said container vertically at a fixed rate, the weight of said collar and beating members being so related to the stiffness of said spring that a vibratory movement will be imparted thereto by the motion of said container.
45. In a washing machine, a casing adapted to contain cleansing liquid and having a vertical bearing in its lower wall, a shaft journaled in said bearing, a cylindrical container secured to the upper end of said shaft coaxially therewith and having a foraminous bottom, means for moving said shaft vertically so as to raise and lower said container, and mechanism carried by said bearing and adapted when said container is in lowered position to impart thereto a vertical reciprocating motion and when the same is in raised position to impart thereto a rotary motion.
46. In a washing machine, a casing adapted to contain cleansing liquid and having a vertical bearing in its lower wall, a shaft journaled in said bearing, a cylindrical container secured to the upper end of said shaft coaxially therewith and having a foraminous bottom, means for moving said shaft vertically so as to raise and lower said container, and mechanism for imparting to said shaft when in lowered position a vertical reciprocating motion, and when the same is in raised position for imparting thereto a continuous rotary motion, the raising and lowering movement of said container by said means being through a greater distance than the amplitude of said reciprocation.
47. In a washing machine, a casing adapted to contain cleansing liquid and having a vertical bearing in its lower wall, a shaft journaled in said bearing, a cylindrical container secured to the upper end of said shaft coaxially therewith and having a foraminous bottom, means for moving said shaft vertically so as to raise and lower said container, and means including a reciprocating connecting rod for imparting to said shaft a vertical reciprocation when the same is in lowered position, the raising and lowering movement of said first means being through a greater distance than said reciprocation and said connecting rod being jointed to permit the raising of said container.
48. In a washing machine, a casing adapted to hold cleansing liquid, said casing having a vertical bearing member in its bottom wall, a shaft journaled in said bearing member, a container of perforated material rigidly secured to the upper end of said shaft, means operative while said container is in lowered position for washing articles therein, means for elevating said shaft so as to bring said container above the liquid level, means operative upon such elevation to arrest the operation of said washing means, and means for thereafter imparting to said shaft a continuous motion of rotation.
49. In a washing machine, a casing adapted to hold cleansing liquid, said casing having a vertical bearing member projecting from its bottom wall, a support for said casing, a shaft slidably and rotatably mounted in said bearing, a cylindrical container of foraminous material secured to the upper end of said shaft, a driving wheel journaled upon the exterior of said bearing and rotatable in a horizontal plane, a bevel gear rotatable with said driving wheel, a second bevel gear pivoted to said bearing member upon a horizontal axis and meshing therewith, an eccentric pin carried by said second gear, a connecting rod pivoted to said pin, means whereby the other end

of said connecting rod is operatively connected to said shaft, a lever pivoted to said support and arranged when depressed to elevate said shaft, and means operative simultaneously with the elevation of said shaft for permitting the bodily rotation of said second gear about said bearing member.

50. In a washing machine, a casing adapted to hold cleansing liquid, said casing having a vertical bearing member projecting from its bottom wall, a support for said casing, a shaft slidably and rotatably mounted in said bearing, a cylindrical container of foraminous material secured to the upper end of said shaft, a driving wheel journaled upon the exterior of said bearing and rotatable in a horizontal plane, a bevel gear rotatable with said driving wheel, a second bevel gear pivoted to said bearing member upon a horizontal axis and meshing therewith, an eccentric pin carried by said second gear, a connecting rod pivoted to said pin, said connecting rod comprising two jointed members forming a toggle joint, a lever pivoted to said support and arranged when depressed to break said toggle and elevate said shaft, the amount of such elevation being greater than the stroke of said connecting rod, and means operative simultaneously with the elevation of said shaft for permitting the bodily rotation of said second gear.

51. In a washing machine, a casing adapted to hold cleansing liquid, said casing having a vertical bearing member projecting from its bottom wall, a support for said casing, a shaft slidably and rotatably mounted in said bearing a foraminous container secured to the upper end of said shaft, a driving wheel journaled upon the exterior of said bearing and rotatable in a horizontal plane, a bevel gear rotatable with said driving wheel, a rotatable collar journaled upon said bearing member below said driving wheel and having a horizontal stud, a second bevel gear journaled upon said stud and meshing with said first gear, an eccentric pin carried by said second gear, a connecting rod having one end pivoted to said pin, and the other end operatively connected to said shaft, a lever pivoted to said support and

arranged when depressed to elevate said shaft, a projecting member carried by said collar, and an extension carried by said lever and normally engaging said member whereby rotation of said collar is prevented, said extension being arranged upon the depression of said lever to release said member and permit said collar to revolve.

52. In a washing machine, a casing adapted to hold cleansing liquid, said casing having a vertical bearing member projecting from its bottom wall, a support for said casing, a shaft slidably and rotatably mounted in said bearing, a foraminous container secured to the upper end of said shaft, a driving wheel journaled upon the exterior of said bearing and rotatable in a horizontal plane, a bevel gear rotatable with said driving wheel, a rotatable collar journaled upon said bearing member below said driving wheel and having a horizontal stud, a second bevel gear journaled upon said stud and meshing with said first gear, an eccentric pin carried by said second gear, a connecting rod having one end pivoted to said pin and the other end operatively connected to said shaft, said connecting rod including a toggle joint, a lever pivoted to said support and arranged when depressed to break said toggle and elevate said shaft, the amount of such elevation being greater than the stroke of said connecting rod, and means movable with said lever and normally engaging a part of said collar whereby the rotation thereof is prevented, said means being engaged to release said collar simultaneously with the breaking of said toggle whereby revolution of said collar is permitted.

53. A washing machine comprising a main container, a garment carrier arranged within the container, mechanical means for vertically reciprocating said carrier, for washing operation and means for independently rotating said carrier.

In testimony whereof, I hereunto affix my signature in the presence of two witnesses.

JAMES B. KIRBY.
